UNITED STATES PATENT OFFICE.

EMIL F. HANSEN, OF PROVIDENCE, RHODE ISLAND.

LINK-MESH MACHINE.

1,192,778.

Specification of Letters Patent. Patented July 25, 1916.

Application filed June 2, 1914. Serial No. 842,504.

To all whom it may concern:

Be it known that I, EMIL F. HANSEN, a citizen of the United States, and resident of the city of Providence, in the county of Providence and State of Rhode Island, have invented certain new and useful Improvements in Link-Mesh Machines, of which the following is a specification.

This invention relates to link forming and closing mechanism and is an improvement 10 on the mechanism disclosed in Patent No. 1,078,317 granted November 11, 1913, to H. W. and C. G. Smith.

The object of this invention is to provide front and rear coöperating formers for 15 engaging and shaping a length of wire into the form of a staple, then link said staple with other links and cause one of the formers to bend the staple into a link, and finally to strike a blow against the bent ends of the link to set them positively and permanently 20 in closed position whereby the ends will more completely and surely abut.

A further object of the invention is to 25 provide a cam adapted to operate one of the forming tools and to provide on this cam a protuberance whereby at the very last end of the inward stroke, the cam causes the former to strike a blow on the ends of the 30 link to positively set them close together.

It is found in the practical operation of machines of this character, particularly on machines for making link-mesh fabric, very difficult, owing to the wear of the tools and 35 the inherent spring in the wire, to bend the link ends so that they will abut and stay in that position when released by the tools. As is well known in this art the close abutting of these link ends is most essential, 40 particularly in the construction of fabric in which the links are designed to be soldered, as it is well known, if the links do not abut, that when heated, the solder in the core of the wire, instead of uniting the ends will 45 run out over the wire and adjacent rings and no joint will be made. Applicant's invention is designed to remedy this defect by striking a blow on the ends like a hammer on an anvil after the wire has been bent into 50 position, which blow has the effect of the hammer blow and will set the wire ends firmly in their bent position so that the ends will not again spring out to open the joint when the link is released.

55 With these and other objects in view, the invention consists of certain novel features

of construction, as will be more fully described and particularly pointed out in the appended claims.

Of the accompanying drawings: Figure 60 1 is a plan view of one form of mesh forming machine showing my improved striking mechanism operatively connected thereto. Fig. 2 is a sectional side elevation on line 2-2 of Fig. 1 looking in the direction of the 65 arrow. Fig. 3 is a plan view showing the forming tools with the length of wire cut off and pressed into one forming tool to shape the same into a staple. Fig. 4 shows the staple as advanced and in the act of being 70 intermeshed with other links. Fig. 5 illustrates the tools as having bent the staple into the form of a link and in position to receive the hammer blow of the actuating cam. Fig. 6 is a detail of the cam showing 75 the protuberance which causes the hammer blow to be struck at the very last end of the inward stroke.

The general construction of the machine herein illustrated is one form to which my 80 improved mechanism is attached and is similar to that fully illustrated and described in the above mentioned patent, in which the table 30 of the machine is described as being provided with bearings 85 31 for four shafts 32, 33, 34 and 35. The shaft 32 is provided with fast and loose pulleys 36, 37, the fast pulley having a crank or handle 38 by which the machine may be 90 manually operated; and the four shafts are 95 geared together by bevel pinions 39 so that they will rotate in unison. The bed 30 also supports a slide 40 on which is mounted the carriage base 41 having brackets 42 for the shaft 43 of the work-feeding pin-roll 95 44. The pins 28 are all spaced to engage links of the fabric as illustrated in Figs. 1 and 2. Suitably supported above and somewhat to the rear of the pin roll is a box 45 in which the roll of completed fabric may be 100 carried. This box is merely a convenience and may be replaced by any other suitable mechanism or device for receiving the work after it leaves the pin-roll. With such a 105 box 45 in use the operator simply occasionally takes up the slack of the fabric behind the roll 44 by revolving the roll of fabric in the box to wind up the fabric.

In Fig. 1 a reel 46 for the wire *a*, which is employed to make the links, is shown as 110 being suitably supported by a spindle 47. From this reel the wire is passed between

upper and lower plates of a friction block 48 (Fig. 1) and is then passed to the feed device which may comprise any usual or suitable mechanism.

5 As more fully described and illustrated in the above-mentioned patent the wire is fed intermittently to the machine, is cut in given lengths, is then bent into the form of a staple *b*, as illustrated in Fig. 3 by the inward movement of the post 50. This post is then withdrawn and the forming tool 51, which extends out rearwardly, see Fig. 1, is engaged and advanced by the cam 52 on the shaft 34 into the position illustrated in Fig. 10 4, where the staple is passed through adjacent links into the rear former 53 which advances on the other side of the mesh to meet it. This rear former then engages and closes the opposite ends of the staple so that they 15 meet around the forming post 54, which forming post serves as an anvil to support the thrust of the rear forming tool 53 and against which the link ends are bent. This rear forming tool, as best illustrated in Fig. 20 5, is connected to the bar 55 which extends rearwardly across the machine and is slidably supported in bearings 56 and 57, its outer end being provided with an adjusting screw 58, the head of which is engaged by 25 the cam 59 mounted on the shaft 32. This cam is provided with a gradual rise along its working face 61 until at the very end of the rise it is provided with a protuberance 62 which has the effect, as the cam is rapidly 30 rotating, of striking a blow like a hammer against the bar 55, the effect of which blow is transmitted through the bar to the forming tool 53 to act upon the abutting ends of the link to strike them against the anvil or 35 supporting post 54, whereby these ends are firmly set and will remain in their bent abutting position when released.

In order to somewhat regulate the force or pressure of the forming tool against the 40 bent ends of the link this screw 58 may be adjusted endwise to lengthen or shorten the bar and is locked by the nut 63.

The carriage base 41 supporting the web of link mesh fabric is moved step by step 45 transversely relative to the forming tools, by means of the cams 64 and 65, see Fig. 1,

which intermittently operate the rack bars 66 and 67 respectively, which rack bars are engaged by pawls 68 on the carriage, the reversing of the carriage travel being accomplished by mechanism fully described and 55 illustrated in the above-mentioned patent.

The above is a description of my improved mechanism as attached to the machine fully illustrated and described in the above mentioned patent, but this striking mechanism is not restricted to use on the special construction of machine shown and described, but may be applied to and operated in connection with any machine for 60 forming links with abutting ends whereby the same may be employed for striking these abutting ends immediately after they are 65 bent.

I claim:

70 1. In a machine of the character described, link forming means, a cam for moving said forming means to bend the wire into a link, said moving cam being provided with means for causing the closing former to strike a 75 blow at the last end of its inward stroke to set the link ends permanently in closed position.

2. In a machine of the character described, link forming means, a cam for moving said forming means to bend the wire into a link, said moving cam being provided with a protuberance for causing the closing former to strike a blow at the last end of its inward stroke to set the link ends permanently in 80 closed position.

3. In a machine of the character described, link forming means, a cam for moving said forming means to bend the wire into a link, said moving cam being provided with means 90 for causing the closing former to strike a blow at the last end of its inward stroke to set the link ends permanently in closed position, and adjustable means whereby the force of the blow may be regulated.

95 In testimony whereof I affix my signature in presence of two witnesses.

EMIL F. HANSEN.

Witnesses:

HOWARD E. BARLOW,
A. F. MACREADY.
